OIL WELL PUMP

George N. Foggan, Pleasantville, Pa.

Application March 30, 1935, Serial No. 13,960

10 Claims. (Cl. 103—179)

The invention aims to provide a new and improved oil well pump in which sand and the like in the oil being pumped, may settle into a sand trap, both during pump operation and when the pump is shut down, and in which the descending sand and the like cannot accumulate around valves, cups, etc., to damage the same.

With the foregoing in view, the invention resides in the novel subject matter hereinafter described and claimed, description being accomplished by reference to the accompanying drawings.

Fig. 1 is an elevation partly in section of a pump constructed in accordance with the invention.

Figs. 2, 3 and 4 jointly disclose a longitudinal sectional view through the pump.

Fig. 5 is a vertical sectional view of the coupling sleeve to which a sand collecting pipe, a sand and oil conducting pipe, and the working barrel of the pump are connected.

Fig. 6 is an end elevation of the coupling sleeve shown in Fig. 5.

A preferred construction has been illustrated and will be rather specifically described, with the understanding however, that within the scope of the invention as claimed, variations may be made.

A cylindrical coupling sleeve is denoted at 10, said sleeve being provided with oil inlet openings 11 and with internal tubular oil inlet means 12 whose ends communicate with said openings, said tubular means 12 being provided with an up-standing sleeve-like boss 13 which communicates therewith, the lower portion of said boss being downwardly tapered internally and constituting a standing valve assembly seat 14. Preferably, the openings 11 are two in number and are diametrically aligned, and the oil inlet means 12 is in the form of a diametrically extending tube integral with the coupling sleeve 10 and integral with the boss 13.

A sand-collecting pipe 15 is threaded into the lower end of the sleeve 10, the lower end of said sand-collecting pipe being closed by a plug or the like 16. A sand and oil conducting pipe 17 is threaded into the upper end of the sleeve 10 and extends to the upper end of the well. This pipe need not be of uniform diameter throughout its length but may be reduced at a suitable point above the principal traveling parts of the pump.

A working barrel 18 is threaded at its lower end into the upper end of the boss 13, and a standing valve assembly 19 is secured in the usual way in the lower end of said working barrel, said

assembly being provided with a tapered lower end 20 engaging the seat 14. The working barrel 18 receives a tubular plunger 21 having a traveling valve 22, and an oil conducting tube 23 is connected to the upper end of the traveling valve cage, said tube 23 extending a suitable distance above the working barrel 18 and being provided at its upper end with a second traveling valve 24 to which a sucker rod 25 is connected, the cage of the valve 24 being of openwork form and discharging into the pipe 17 whereas the cage of the valve 22 is of closed form and communicates only with the tube 23 and the plunger 21.

A guiding sleeve 26 is provided for the oil conducting tube 23, said guiding sleeve being tightly secured in the upper end of the working barrel 18. The sleeve 26 projects above the working barrel 18 and the upper end of said sleeve is relatively small internally as denoted at 27 to slidably engage the tube 23. From the portion 27 to the lower end of the sleeve 26, the internal diameter of the latter is relatively large to provide an oil-receiving chamber 28 around the tube 23. Oil-conducting passages 29 extend outwardly from this chamber and open through the periphery of the sleeve 26 in the portion of the latter which projects above the working barrel 18. As the pump operates, oil may flow into and out of the working barrel 18 through the passages 29 and chamber 28 so that no objectionable pressure or vacuum will be created in said working barrel above the plunger 21 to interfere with free operation of the latter.

During reciprocation of the plunger 21, oil from the well enters the oil inlet means 12 through the openings 11, ascends through the standing valve assembly 19 into the working barrel 18, flows through the plunger 21, tube 23 and traveling valves 22 and 24, and discharges into the pipe 17. The oil is, of course, pumped on to the upper end of the well and any sand and the like therein may gravitate in the pipe 17, pass through the coupling sleeve 10 and enter the pipe 15 in which it is trapped. None of the descending sand and the like can enter the working barrel 18 from which it is excluded by the guide sleeve 26. Both when the pump is in operation and when it is shut down, sand and the like may settle through the oil into the trap 15 and cannot accumulate around valves, cups, etc. to damage the same.

It will be seen from the foregoing that a comparatively simple construction has been provided for attaining the desired end in an effective manner, and while preferred features of construction

have been shown, attention is again invited to the possibility of making variations within the scope of the invention as claimed.

I claim:

- 5 1. An oil well pump comprising a tubular pipe coupling having oil intake openings and tubular oil intake means whose ends communicate with said openings, said oil intake means being provided with a central upstanding sleeve-like boss 10 whose interior opens into said oil intake means, a sand-collecting pipe whose upper end is connected to the lower end of said coupling, a pipe for conducting oil to the top of the well and conducting sand to said sand-collecting pipe, the lower end of said oil and sand conducting pipe being connected to said 15 lower end of said oil and sand conducting pipe being connected to the upper end of said coupling, a working barrel within and spaced from said oil and sand conducting pipe, the lower end of said working barrel being connected to said 20 sleeve-like boss to receive oil from said oil intake means, a standing valve assembly in said lower end of said working barrel, a plunger in said working barrel having a traveling valve, plunger operating means connected to said 25 plunger, and means for preventing sand from descending into said working barrel.
2. An oil well pump comprising a tubular pipe coupling having oil intake openings and tubular oil intake means whose ends communicate with 30 said openings, said oil intake means being provided with a central upstanding sleeve-like boss whose interior opens into said oil intake means, a sand-collecting pipe whose upper end is connected to the lower end of said coupling, a pipe 35 for conducting oil to the top of the well and conducting sand to said sand-collecting pipe, the lower end of said oil and sand conducting pipe being connected to the upper end of said coupling, a working barrel within and spaced from said oil 40 and sand conducting pipe, the lower end of said working barrel being connected to said sleeve-like boss to receive oil from said oil intake means, a standing valve assembly in said lower end of said working barrel, a tubular plunger in said 45 working barrel having a traveling valve, an oil conducting tube having its lower end connected to said tubular plunger to receive oil therefrom, said oil conducting tube extending above said working barrel and discharging at its upper end 50 into said oil and sand conducting pipe, a guide for said oil conducting tube carried by the upper end of said working barrel and constructed to prevent sand from descending into said working barrel, and a sucker rod connected to the upper end of said oil conducting tube.
3. An oil well pump comprising a tubular pipe coupling having oil intake openings and tubular oil intake means whose ends communicate with 55 said openings, said oil intake means being provided with a central upstanding sleeve-like boss whose interior opens into said oil intake means, a sand-collecting pipe whose upper end is connected to the lower end of said coupling, a pipe for conducting oil to the top of the well and conducting sand to said sand-collecting pipe, the lower end of said oil and sand conducting pipe being connected to the upper end of said coupling, a working barrel within and spaced from said oil and sand conducting pipe, the lower end of said working barrel being connected to said sleeve-like boss to receive oil from said oil intake means, a standing valve assembly in said lower end of said working barrel, a tubular plunger in said working barrel having a traveling valve, an oil conducting tube 65 connected with and communicating with said plunger for reciprocating the same; a guide sleeve secured in and projecting above the upper end of said working barrel, said guide sleeve having an upper portion of relatively small internal diameter slidably engaging said tube and being of larger internal diameter from said internally 70 small portion to its lower end to provide an oil chamber within said sleeve around said tube, said sleeve having oil conducting ports from said chamber to the periphery of its upwardly projecting portion.
4. An oil well pump comprising a tubular pipe coupling having oil intake openings and tubular oil intake means whose ends communicate with 75 said openings, said oil intake means being provided with a central upstanding sleeve-like boss whose interior opens into said tube; pipes connected with the ends of said coupling, and a working barrel connected with the upper end of said boss.
5. In a pump of the class described having a working barrel provided with a standing valve, a tubular plunger in said working barrel provided with a traveling valve and an oil conducting tube connected with and communicating with said plunger for reciprocating the same; a guide sleeve secured in and projecting above the upper end of said working barrel, said guide sleeve having an upper portion of relatively small internal diameter slidably engaging said tube and being of larger internal diameter from said internally 80 small portion to its lower end to provide an oil chamber within said sleeve around said tube, said sleeve having oil conducting ports from said chamber to the periphery of its upwardly projecting portion.
6. In an oil well pump, a working barrel, a guide sleeve secured within and projecting above the upper end of said working barrel, said sleeve being of relatively small internal diameter toward its upper end and being of relatively large internal diameter throughout the remainder of its length, said sleeve having oil ports leading from its larger interior portion to the periphery of said sleeve above said working barrel, a tube passing slidably through and guided by said guide sleeve, and a working valve carried by said tube within said working barrel.
7. In a pump of the class described, a tubular pipe coupling having diametrically opposed oil intake openings and a single diametrical oil intake tube whose ends communicate with said openings, said tube being provided with a central upstanding sleeve-like boss whose interior opens into said tube; pipes connected with the ends of said coupling, and a working barrel connected with the upper end of said boss.
8. In a pump of the class described, a tubular pipe coupling having diametrically opposed oil intake openings and a single diametrical oil intake tube whose ends communicate with said openings, said tube being provided with a central upstanding sleeve-like boss whose interior opens into said tube; pipes connected with the ends of said coupling, and a working barrel connected with the upper end of said boss.

tube having its lower end connected to said tubular plunger to receive oil therefrom, said oil conducting tube extending above said working barrel and having a second traveling valve at its upper end which discharges into said oil and sand conducting pipe, a sucker rod connected to said second traveling valve, and a guide for said oil conducting tube carried by the upper end of said working barrel and constructed to prevent sand from descending into said working barrel.

4. An oil well pump comprising a tubular pipe coupling having oil intake openings and tubular oil intake means whose ends communicate with said openings, said oil intake means being provided with a central upstanding sleeve-like boss whose interior opens into said oil intake means, the lower end portion of said boss being downwardly tapered internally and constituting a standing valve assembly seat, a sand-collecting pipe whose upper end is connected to the lower end of said coupling, a pipe for conducting oil to the top of the well and conducting sand to said sand-collecting pipe, the lower end of said oil and sand conducting pipe being connected to the upper end of said coupling, a working barrel within and spaced from said oil and sand conducting pipe, the lower end of said working barrel being connected to said sleeve-like boss to receive oil from said oil intake means, a standing valve assembly in said lower end of said working barrel and having a conical lower end engaged with said seat, a plunger in said working barrel, plunger operating means connected to said plunger, and means for preventing sand from descending into said working barrel.

5. In a pump of the class described having a working barrel provided with a standing valve, a tubular plunger in said working barrel provided with a traveling valve and an oil conducting tube connected with and communicating with said plunger for reciprocating the same; a guide sleeve secured in and projecting above the upper end of said working barrel, said guide sleeve having an upper portion of relatively small internal diameter slidably engaging said tube and being of larger internal diameter from said internally small portion to its lower end to provide an oil chamber within said sleeve around said tube, said sleeve having oil conducting ports from said chamber to the periphery of its upwardly projecting portion.

6. In an oil well pump, a working barrel, a guide sleeve secured within and projecting above the upper end of said working barrel, said sleeve being of relatively small internal diameter toward its upper end and being of relatively large internal diameter throughout the remainder of its length, said sleeve having oil ports leading from its larger interior portion to the periphery of said sleeve above said working barrel, a tube passing slidably through and guided by said guide sleeve, and a working valve carried by said tube within said working barrel.

7. In a pump of the class described, a tubular pipe coupling having diametrically opposed oil intake openings and a single diametrical oil intake tube whose ends communicate with said openings, said tube being provided with a central upstanding sleeve-like boss whose interior opens into said tube; pipes connected with the ends of said coupling, and a working barrel connected with the upper end of said boss.

8. In a pump of the class described, a tubular pipe coupling having diametrically opposed oil intake openings and a single diametrical oil intake tube whose ends communicate with said openings, said tube being provided with a central upstanding sleeve-like boss whose interior opens into said tube; pipes connected with the ends of said coupling, and a working barrel connected with the upper end of said boss.

take tube whose ends communicate with said openings, said tube being provided with a central upstanding sleeve-like boss whose interior opens into said tube; pipes connected with the ends of said coupling, a working barrel connected with the upper end of said boss, and a standing valve in the lower end of said working barrel, said boss having a downwardly tapered internal lower end

portion constituting a seat for said standing valve.

9. A structure as specified in claim 7; said coupling, tube and boss being integrally joined to each other.

10. A structure as specified in claim 8; said coupling, tube and boss being integrally joined to each other. 5

GEORGE N. FOGGAN.
